UNITED STATES PATENT OFFICE.

ALFRED HILL, OF CATHLAMET, WASHINGTON.

COMBINATION WRENCH AND PIPE-CUTTER.

1,075,649.

Specification of Letters Patent. Patented Oct. 14, 1913.

Application filed February 13, 1913. Serial No. 748,170.

To all whom it may concern:

Be it known that I, ALFRED HILL, a subject of the Czar of Russia, residing at Cathlamet, in the county of Wahkiakum and State of Washington, have invented a new and useful Combination Wrench and Pipe-Cutter, of which the following is a specification.

The present invention appertains to a combination tool, and aims to provide a tool or implement combining an ordinary wrench, a pipe wrench and a pipe cutter.

The present invention also aims to provide a device of the character indicated which shall be comparatively simple, and inexpensive in construction, as well as convenient, and serviceable in its use, it also being the object of the invention to improve generally and to increase the utility of devices of that character to which the present invention appertains.

With the foregoing and other objects in view which will appear as the description proceeds, the invention resides in the combination and arrangement of parts and in the details of construction hereinafter described and claimed, it being understood that changes in the precise embodiment of invention can be made within the scope of what is claimed without departing from the spirit of the invention.

The invention has been illustrated in its preferred embodiment in the accompanying drawing, wherein corresponding reference characters have been employed to denote corresponding parts, and wherein:

Figure 1 is a side elevation of the implement as employed as a pipe wrench, parts being broken away. Fig. 2 is a sectional view taken on the line 2-2 of Fig. 1, showing the device as employed for cutting pipes or other circular stock. Fig. 3 is a sectional view taken on the line 3-3 of Fig. 1, showing the movable jaw provided with a rotatory cutter, as in Fig. 2. Fig. 4 is a plan view of the key for swiveling the inner end of the actuating rod to the movable jaw. Fig. 5 is a side elevation, and Fig. 6 is a perspective view of one of the supplemental or auxiliary jaws for gripping a pipe or other circular stock. Fig. 7 is a side elevation of a modified form of the invention, parts being broken away. Fig. 8 is a sectional detail through the movable jaw of the form shown

in Fig. 7. Fig. 9 is a fragmental perspective of another variation, and Fig. 10 is a section detail of the variation illustrated in Fig. 9.

Referring specifically to the drawing, the numeral 7 designates the stock, handle or body of the implement which is preferably fashioned from a flat bar and has its neck portion 8 off-set, but lying in the same plane. The upper or inner end of the body is provided with a head or stationary jaw 9, which may be said to be in alinement with the lower or outer portion of the body. The stationary jaw 9, neck 8, and the body or handle 7 are preferably integral. The movable jaw has been designated generally by the numeral 10, the same comprising a block or jaw proper 11 having a cheek 12 bearing against or fitting one side of the neck 8, and a second or independent cheek 13 lying against or fitting the other side of the neck and abutting against the cheek 12 at the edges of the neck. The cheeks are secured together at the edges of the neck 8 by means of screws 14 passing through the end portions of the cheek 13 and screw threaded into the cheek 12, the cheek 13 abutting or fitting against the shoulder of the block 11 formed by the cheek 12, and the two cheeks preferably being provided with the inner ribs 15 engaging in the longitudinal channels 16 in the sides of the neck.

The complementary faces of the jaws are flat with the exception that the respective jaws 9 and 10 are provided with the recesses 17 and 17' in their faces. These recesses are comparatively narrow, concaved and deep, and are parallel with the sides of the jaws. Tapered pins 18 and 18' are also carried by the respective jaws 9 and 10 and pass through the recesses 17 and 17', the pins being readily removable therefrom or insertible into the jaws.

Ordinarily, when the faces of the jaws are unobstructed, by the attachments herein-after described the device may be employed in the usual capacity of a wrench for nuts and other objects, the recesses 17 and 17' being such as not to interfere with the utility of the device as a nut wrench or the like. In order that the device may be employed as a pipe cutter, the rotatory cutters or disks 19 and 19' are adapted to fit into the respective recesses 17 and 17' of the jaws, the pins 18

and 18' having been withdrawn and then having been again inserted to pass through the central apertures which are provided in the cutters. In this manner, the cutters are 5 mounted for rotation within the jaws, and project partially from the faces of the jaws in such a manner that when the jaws are brought together, the cutters are designed to properly engage the pipe or other stock for 10 effecting the cutting thereof, as will be understood.

In order that the device may be employed as a wrench for pipes or other circular stock, instead of employing the cutters, a pair of 15 supplemental or auxiliary jaws 20 are employed, the same being of a contour similar to the jaws 9 and 10 and having their faces properly toothed. The backs of the supplemental jaws 20 are provided with the ears 20 21 and are adapted to enter or fit within the respective recesses 17 and 17' of the jaws, so that the locking pins may be passed through apertures in the ears to retain the supplemental jaws in position.

25 The supplemental jaws are adapted to grip the pipe or other stock so that it may be properly rotated or held in a stationary position, whichever is desired. The supplemental jaws are designed to fit against the 30 faces of the permanent or primary jaws, so that the pins 18 and 18' are not subjected to undue strain.

The means for actuating the movable jaw consists in an actuating rod 22 screw threaded 35 through the lower or main portion of the stock or body 7, and provided at its outer end with suitable hand hold 23, the rod being provided at its inner end with an annular or circumferential groove 24 providing a 40 neck 25 and a head 26. The inner end of the actuating rod 22 is adapted to fit within a pocket 27 in the bottom of the movable jaw 10, and the movable jaw is also provided with a dove-tailed channel 28 opening at one 45 side and receiving a dove-tailed key 29 having an open slot 30. The open slot 30 of the key is adapted to receive the neck 25 of the actuating rod, the key straddling said neck in order that the head 26 may set on the key 50 for constraining the actuating rod and movable jaw from separation but permitting a rotatory movement of the former. The actuating rod is thus swiveled effectively to the movable jaw, and by rotating the rod, it 55 may be made to travel inwardly or outwardly, accordingly moving the movable jaw.

It will be evident from the foregoing, that the various parts are readily assembled and 60 also readily capable of separation for the purpose of cleaning, repair or replacement.

As above indicated, the device may ordinarily be employed in the capacity of a nut wrench or the like, and either the cutters or

the supplemental jaws may be applied to the 65 jaws 9 and 10, so that the device may be employed in the capacity of a pipe cutter or a pipe wrench.

In the form depicted in Fig. 7, the stock or handle 7' is provided with the offset neck 70 8' having the stationary jaw 9', the movable jaw 11' slidably engaging the neck 8' as in the form above described. In this modified form the stationary jaw 9' is provided with a pair of recesses 17^a into which the rollers 75 19^a are adapted to fit, tapered pins 18^a being passed through the jaw 9' to journal the rollers 19^a in the recesses 17^a. The rollers 19^a are adapted to engage one side of the pipe or the stock to be cut, while the cutter 80 19' carried by the movable jaw engages the other side. In this modified form, there is also disclosed a tapered pin or key 29' carried by the movable jaw and engaging through one side of the groove 24' of the actuating bar 22'.

In the variation illustrated in Figs. 9 and 10, the movable jaw or block 11'' is provided with a lower cut away portion or rabbet 31 extending away from the shoulder provided 90 by the block and its cheek and the cheek 13'' is provided with an extension 32 normally fitting in the cut away portion or rabbet 31, the extension 32 and the adjoining portion of the jaw 11' having complementary notches to embrace the inner end or head of the actuating rod so as to swivel the inner end of the actuating rod to the movable jaw, and the inner end of the rod engaging snugly with the block, in order to 100 jam directly against the solid block 11'' when the rod is adjusted toward the stationary jaw.

What is claimed is:—

1. In a device of the character described, 105 a stock having a jaw at one end, a movable jaw embodying a solid block having a cheek fitting one side of the stock and forming a shoulder, a cheek fitting the other side of the stock and abutting against the said shoulder, the cheeks abutting at the edges of the stock, means for securing the cheeks together at the edges of the stock, and an actuating rod in screw-threaded engagement with the stock and having one end swiveled to the 110 said block, the said end engaging snugly within the block.

2. In a device of the character described, 115 a stock having a jaw at one end, a movable jaw embodying a solid block having a cheek 120 fitting one side of the stock and forming a shoulder, a cheek fitting the other side of the stock and abutting against the said shoulder, the cheeks abutting at the edges of the stock, means for securing the cheeks 125 together at the edges of the stock, an actuating rod in screw threaded engagement with the stock and having a circumferential

groove at its inner end, the block having a lower rabbet extending away from the shoulder and the last mentioned cheek having an extension fitting in the rabbet, the 5 rabbet and extension having complementary notches to embrace the inner end of the actuating rod, and the inner end of the actuating rod engaging snugly within the block.

In testimony that I claim the foregoing as my own, I have hereto affixed my signature 10 in the presence of two witnesses.

ALFRED HILL.
